MEASURING DISPENSER

Raymond C. Penfield, Chicago, Ill.

Application July 1, 1946, Serial No. 680,587

3 Claims. (Cl. 222—364)

1

This invention relates in general to cartons for various loose materials such as coffee, rice, soap chips, and many other materials which it is often desirable to discharge in definite quantities.

An important object of the invention is to provide a measuring dispenser for cartons in which the dispenser and the carton are all made from the same blank or piece of material.

A further object of the invention is to provide an improved measuring dispenser which may be effectively sealed before the carton is used and in which the dispenser is movable to open and close the dispensing opening.

Still a further object of the invention is to provide a carton with a measuring dispenser cut from the same blank of material and substantially conserving the amount of additional stock which is used for the blank so that the entire carton may be produced at a minimum cost with a minimum loss of material.

Still a further object of the invention is to provide a combined carton and dispenser which is effective and efficient in operation, easily erected for filling the carton with material to be dispensed, and the dispenser readily movable in the carton from its closed or sealed position.

Other objects of the invention will appear in the specification and will be apparent from the accompanying drawings in which,

Fig. 1 is a plan view of a blank of sheet material from which the dispensing carton of this invention is formed;

Fig. 2 is a perspective view of a carton in accordance with this invention in assembled and closed condition;

Fig. 3 is a fragmentary perspective showing the measuring dispenser of the carton in open position;

Fig. 4 is a sectional view of the carton as taken on the line 4—4 of Fig. 2;

Fig. 5 is a transverse section of the container as taken on the line 5—5 of Fig. 2;

Fig. 6 is a fragmentary sectional view showing the dispenser in closed position and the carton tipped to fill the dispenser with the material of the carton;

Fig. 7 is a fragmentary sectional view showing the measuring dispenser in open or dispensing position and the carton raised and partially tilted for discharging the material from the dispenser; and

Fig. 8 is a perspective view showing the dispenser as partially assembled before it is inserted in the carton.

Various types of pouring and discharging de-

vices have been proposed in connection with cartons of various kinds. Some of these dispensers are fixed in position and some of them are separately produced and attached in various ways to the carton. The present invention has the advantage that it is formed of the material of the carton itself; is foldable in the carton when the carton is made and therefor provides a suitable seal for the material within the carton, and is movable in and as a part of the carton for dispensing material therefrom.

Referring now more particularly to the drawings, a carton in accordance with this invention, is made from a blank of sheet material such as cardboard, or any other suitable material, cut, scored and shaped to form connected opposite carton sides 10 and 11, ends 12 and 13, and a lapping connection flap 14. At the tops and bottoms of the sides are corresponding closing flaps 15 and 16. One of the ends 13 has top and bottom flaps 17 and 18, and the other end 12 has a bottom flap 19 and an integrally connected top structure providing the measuring dispenser of this invention.

25 A portion 20 of the end 12 is connected by scored, weakened, or partially severed lines 21 to the adjacent carton sides 10 and 11 and to the end by a scored hinge line 22. Extending outwardly from the end portion 20 is a tab portion 23 which projects slightly beyond the tops of the sides 10 and 11 and is separated from the flaps 15 by the cuts 24.

30 Continuing outwardly between the top flaps 15 in the blank form is a double wall portion 25 connected to the tab portion 23 by a scored fold line 26. This wall portion 25 is of a length equal to the tab portion 23 and the end portion 20, and in assembly they are folded together or are doubled upon each other as shown more clearly in Figs. 4 and 6.

35 The outer end of this double wall portion 25 extends (in the blank) beyond the outer edges of the top flaps 15, and connected to it by a fold line 27 is a foldable dispenser comprising a bottom wall 28 with sides 29 hinged thereto on fold lines 30. Each side has a flap 31 connected thereto by a scored hinge line 32 and the outer edge of each flap being separated from the adjacent end flap 15 by a cut 33. At the outer edge 40 of each side 29 is an angular flat portion 34 to form a stop when the carton is assembled.

45 With this blank construction and formation, the measuring dispenser is preferably assembled partially before the carton is set up. This is effected by bending the bottom wall 28 substan-

tially at right angles to the double wall portion 25 upon fold line 27 and swinging the sides 29 upon their fold lines 30 until their flaps 31 may be folded and adhesively secured to the under side of wall portion 25, as shown more clearly in Fig. 8. The wall portion 25 and the flaps 31 are then doubled upon and adhesively secured to the inside of tab portion 23 and carton end wall portion 20, the flaps 31 being thus secured between wall portions 25 and 20, thereby securely connecting the dispenser for incorporation into the container.

In erecting the container, the dispenser is disposed inwardly, the flaps 15 and 17 being overlapped and secured at the end, with the tab 23 extending outwardly as shown in Fig. 2 or folded and adhesively or otherwise secured against the top of the container as indicated in broken outline in this figure.

For filling purposes, the opposite or bottom end is left open, but after being filled, the bottom is sealed in any well known manner and the top or dispensing end is placed uppermost. The upper end is sealed at the dispenser by the weakened lines 21 and the contact or overlapping of the doubled tab portion 23 with the carton ends 15. By releasing the tab portion, grasping and pulling it outwardly from the carton, the weakened lines 21 are severed and the dispenser is swung outwardly upon hinge line 22 until the angular portions 34 of the side walls 29 engages the inner side of the innermost flap 15, as clearly shown in Figs. 3 and 7.

To fill the dispenser with material 35 from within the container, the dispenser is closed as shown in Fig. 6 and the container is up-ended or tipped to lodge the material therein. When the dispenser is turned outwardly, it will discharge a predetermined measured quantity depending in amount upon the particular material.

While a preferred embodiment of the invention has been thus particularly described, it should be regarded by way of illustration and not as a limitation of the invention as various changes may be made in the construction, combination and arrangement of the parts without departing from the spirit and scope of the invention.

I claim:

1. A measuring dispenser, comprising a carton of sheet material and a relatively rotatable dispensing device formed integrally of the same sheet blank, the carton having side and end walls and one of the end walls having a partially weakened portion between it and the adjacent side wall and having a fold line at the bottom of the weakened portion, this weakened end being extended to provide the dispensing device which is foldable together to form an open container and has a wall secured to the weakened wall portion of the carton and also to provide a doubled tab extending from the end of the carton when

the carton is extended in set-up position, this doubled tab portion being foldable over and against the end of the carton.

2. A carton of sheet material and a rotatable measuring dispenser device formed integrally of the same sheet blank, the carton having connected side and end walls and the extremity of one end between the end wall and the side wall being weakened at the sides of the end wall with a fold line at the bottom of the weakened portion and extending beyond the ends to provide an angular open container with a portion which when doubled upon itself provides a tab extending beyond the end of the carton, an extension of the doubled portion being foldable to form a bottom and side walls with connecting flaps extending from the side walls and insertable between the said doubled walls to hold them together, the dispenser container thus formed being sealed against the carton walls in setting up the carton and the dispensing device being rotatable upon the said fold line from within the carton to project therefrom when the weakened portion is severed by pulling outwardly upon the tab portion, the side walls of the dispenser having an angular portion adjacent the bottom of the dispenser for engaging the end of the carton to limit the outer movement of the dispenser from the carton.

3. A carton of sheet material and a relatively rotatable measuring device made integrally of the same sheet blank, the device being in the form of an open angular container having a double wall portion folded upon itself and with an extended portion which forms a tab to project from the carton, one of said double wall portions being in common with a portion of the carton wall and partially severable therefrom but to hinge thereon, and the device being so partially severed by means of the projecting tab and thereafter rotatable by the tab from within the carton and into and out of the opening formed by the severed wall portion.
